UNITED STATES PATENT OFFICE

2,395,056

APPARATUS FOR PROTECTING SHIPS FROM
TORPEDOES, MINES, AND THE LIKE

Charles H. Luby, Philadelphia, Pa.

Application January 14, 1943, Serial No. 472,312

4 Claims. (Cl. 114—240)

This invention relates to method and apparatus for protecting ships from torpedoes, mines, and the like.

Generally speaking, the apparatus in accordance with this invention, from a description of the use of which the method in accordance with this invention will appear, comprises a pair of nets arranged to be immersed at a distance off the sides of a ship and to be towed by the ship in certain relation to the sides when the ship is under way. By virtue of the relationship established between the nets and the sides of the ship when it is under way, the nets will operate variously to entangle and divert a torpedo or explode it at a distance from the ship.

The nets, by virtue of their relationship to the sides of a ship, will operate to prevent mines from coming into contact with the ship's sides, or act to explode them by contact at a distance from the ship's side.

The apparatus and method in accordance with this invention, broadly and in various detail, will, it is believed, be readily understood from the following description of apparatus embodying the invention and of its mode of operation with reference to the drawings, in which:

Figure 1 is a plan view of a portion of a ship in combination with apparatus in accordance with this invention.

Figure 2 is a fragmentary side elevation of the subject of Figure 1.

Figures 3 and 4 are views showing details of construction.

Referring to the several figures, A indicates a ship, while B, B indicate a pair of nets extending along the sides of the ship from points off the bows for a distance toward the stern. If desired, the nets may extend the full length of the ship and desirably, in any event, in practice will extend upwards of two-thirds of the length to protect the vital parts thereof.

The nets as shown in Figure 3, and which are identical for both sides of the ship, may comprise, for example, a series of wire cable cargo nets 1 formed, for example, from $\frac{3}{8}$ inch wire rope secured at their tops to a length of 1 inch galvanized cable 2, by means of shackles 3, and at their lower ends to a length of $1\frac{1}{2}$ inches galvanized wire cable 2', by means of shackles 3. The nets 1 will be secured together at intervals along their adjacent edges by shackles 3'.

The galvanized wire cables 2, 2' may be the usual towing cables customarily carried by ships.

The net is floated in vertical position, as shown, by means of rafts 5, 5, each connected at one

aft corner to one end of the upper cable 2, 2, and floats 6, 6, connected at one end to the cable 2 at intervals between its ends. The rafts 5, 5 may be constructed of balsa logs secured together and the floats 6, 6 may be comprised of balsa wood. The size of the rafts and of the floats will, of course, be dependent upon the weight of the net to be floated.

Each of the rafts 5, 5 will be equipped with a center board 7, arranged obliquely so that when the net and rafts are towed by the ship, the rafts and net will be carried away from the side of the ship.

For towing of the nets a boom 8 of wood or steel extends forward at the very prow of the ship. The forward rafts 5 of the nets on opposite sides of the ship are connected to the boom 8 at a forward corner thereof and at the same side of the raft to which the cables 2, 2 are connected by means of towing cables 9, through the medium of free-riding rings 10, 10'; and the lower forward corners of the nets are connected to the free-riding rings 10, 10' by means of cables 9'.

The forward rafts 5 are also connected to the ship by means of mooring lines 11, 11, while the rafts 5, 5 at the aft ends of the cables 2, 2 are connected to forward corners thereof, and the aft corners of said rafts at the same sides of the rafts are connected to the ship by mooring lines 12, 12 and the lower after corners of the nets are connected to the ship by means of mooring lines 12', 12', the mooring lines 12, 12 and 12', 12' being of greater length than are the mooring lines 11, 11. The several mooring lines are desirably connected to the ship through the medium of free-riding rings, as in the case of the towing lines 9, 9 and 9', 9', so that in the event that the ship sinks the rafts 5, 5 will float free.

For convenience in assembling and handling the nets B, a plurality of brackets 13, as shown in Figure 4, are supported from the ship's rail at intervals on both sides of the ship. The brackets are provided with pins 14, 14 between which, for assembly of the nets, the cables 2 and 2' and the cables forming the upper and lower edges of the cargo nets may be laid.

With the arrangement shown in Figure 4, it will be apparent that the clamps or shackles 3 and 3' may be readily applied to secure the several cargo nets together and to the cables 2 and 2'. It is also apparent that the net having been assembled can be supported, as shown in Figure 4, by the brackets 13 until its use is desired, and that from such support it can be readily lowered.

into the water by first putting over the lower cable 2' and lowering the net by its upper cable 2.

Again, when it is desired to inspect or repair the net, or when it is desired that it be put out of use, it may be readily hauled up to support by the brackets.

The raising and lowering of the net will be accomplished in any convenient manner with use of the ship's tackle, it being noted that hauling lines connected to the rafts will desirably be connected to their outer edges to the end that the center boards will extend away from the ship's side as the rafts are hauled in.

Variously, where necessary, chaffing gear will be provided to protect the sides of the ship when the nets are under tow, as, for example, by the provision of a log boom or spar 15 placed to prevent damage to the ship's bows from rubbing or thrashing of the towing cables 9.

In the operation of the nets B, when it is desired to protect the ship A from torpedo attack or from mines, the nets B, B with their supporting rafts and floats and with the towing cables and mooring lines attached, are lowered into the water. As the ship proceeds, the nets are towed along with it and due to the oblique arrangement of the center boards under the rafts 5, and in the case of the forward rafts, the wash from the bow of the ship, the rafts tend to go away from the sides of the ship. Due to the length of the towing cables 9 and the arrangement of the mooring cables, the nets B will assume an angular relationship to the sides of the ship from their forward to their after ends. Thus, the nets will lie off at a distance from the side of the ship with their forward ends closer to the sides than are their after ends, for example, as shown, in Figure 1, or at a greater angle, as, for example, an angle of 45°, to the center line of the ship than is shown.

As the nets are towed along, they will tend, as is indicated in Figure 1, to undulate both in their fore and aft extension and in their vertical extension.

It will now be apparent that a torpedo traveling toward a side of the ship will of necessity strike the net before it can strike the ship's side. Since the net is moving along with the ship in a direction oblique to the course of the ship, and with an undulating motion, the torpedo, if it be not fired by contact with the net, but rather penetrate to a greater or less extent, will be diverted from its course and, if it pass through the net, will strike the side of the ship out of line therewith so that its striker will not contact with the ship and it will not be fired.

In the case of mines, the nets will operate to fend off or explode mines, with which they may come in contact.

What I claim and desire to protect by Letters Patent is:

1. In combination with a ship, means for floating a net substantially vertically comprising a forward raft and an aft raft, a tow line connected to a corner at the forward end of the forward raft and to the ship, a connection between the net and an aft corner of said raft at the same side thereof as the connection to the tow line, a connection between the aft end of the net and the aft float, and an obliquely extending center-board on the bottom of the forward raft, whereby the net will be towed by the ship and spaced therefrom.

2. In combination with a ship, means for floating a net substantially vertically comprising a forward raft and an aft raft, a tow line connected to a corner at the forward end of the forward raft and to the ship, a connection between the net and an aft corner of said raft at the same side thereof as the connection to the tow line, a connection between the aft end of the net and the aft float, and an obliquely extending center-board on the bottom of the forward raft extending from the corner of the raft to which the net is connected, whereby the net will be towed by the ship and spaced therefrom.

3. In combination with a ship, means for floating a net substantially vertically comprising a forward raft and an aft raft, a tow line connected to a corner at the forward end of the forward raft, a connection between the net and an aft corner of said forward raft at the same side thereof as the connection to the tow line, an obliquely extending center-board on the bottom of the forward raft extending from the corner of the raft to which the net is connected, a connection between the aft end of the net and a corner at the forward end of the aft raft, a connection between the aft end of the aft raft at the same side to which the net is connected between the ship and the aft raft, and an obliquely extending center-board on the bottom of the aft raft.

4. In combination with a ship, means for floating a net substantially vertically comprising a forward raft and an aft raft, a tow line connected to a corner at the forward end of the forward raft and to the ship, a connection between the net and an aft corner of said raft at the same side thereof as the connection to the tow line, a connection between the aft end of the net and the aft float, an obliquely extending center-board on the bottom of the forward raft extending from the corner of the raft to which the net is connected, and a plurality of floats connected at one end only to the net between the rafts.

CHARLES H. LUBY.
